United States Patent Office

Des. 225,809
Patented Jan. 9, 1973

225,809

STUDENT DESK

Frank R. Torrey, 9805 Dallas Ave.,
Silver Spring, Md. 20901

Filed Feb. 19, 1971, Ser. No. 117,194

Term of patent 14 years

Int. Cl. D6—04

U.S. Cl. D6—181

FIG. 1

FIG. 2

FIG. 3

FIG. 1 is a perspective view of a student desk, showing my new design;

FIG. 2 is a rear elevational view thereof, and

FIG. 3 is a side elevational view thereof, the other side being a mirror image thereof.

I claim:

The ornamental design for a student desk, as shown and described.
